UNITED STATES PATENT OFFICE.

HENRY S. VOGEL, OF GRANT CITY, MISSOURI.

GAME

1,396,795.

Specification of Letters Patent. Patented Nov. 15, 1921.

Application filed January 23, 1920. Serial No. 353,420.

To all whom it may concern:

Be it known that I, HENRY S. VOGEL, a citizen of the United States, residing at Grant City, in the county of Worth and 5 State of Missouri, have invented certain new and useful Improvements in a Game, of which the following is a specification.

The invention relates to game devices whereby one is enabled to pass idle moments 10 in a pleasant way and at the same time train the mind to be on the alert whereby to grasp and take advantage of opportunities.

The invention relates to the class of games embodying a deck of cards, which in playing 15 embodies trumps and suit, the cards having a designated value and the player making the most points in any hand being the winner thereof.

The game deals with incidents of warfare 20 and acquaints one with the various phases thereof and is designated by the name "Patrol, a game of No Man's Land."

Referring to the accompanying drawings:

25 Figures 1, 2, 3 and 4 represent the suit cards, any one of which may be trumps.

Fig. 5 represents one of a series of suit cards which may never be trumps.

Fig. 6 represents the long master card.

30 Fig. 7 represents the back of the cards which is suggestive of a patrol passing through a rural district or uninhabited section of country.

The game is essentially one for the parlor 35 or indoors and comprises a pack or deck of cards embodying forty-nine in number. It is to be understood that any number of cards may be deducted in order that the game may be more interesting to the players.

40 The cards are numbered from one to ten inclusive, in each of four suits; and from one to eight, inclusive of one odd suit; and contains one odd card called Patrol. The four suits containing cards numbered from one to ten, are the only suits which may be named trump.

The suits are as follows:

Machine gun.—Consisting of ten cards, 50 each card bearing an illustration of a machine gun in action, with a machine gun crew working the gun. This card is colored red and green, besides the other minor colors necessary.

55 Sniper.—Consisting of ten cards, each

card bearing an illustration of a sniper mounted in a tree, in the act of firing on an enemy. This card is colored green, the trunk of the tree is gray, and other minor colors are also present.

Trench mortar.—Consisting of ten cards, each bearing an illustration of a trench mortar set for action, and a crew working the gun. This card is colored red, and contains the minor colors of earth color, for the earth 60 embankment or trench, and the colors necessary to the scene.

Hand grenade.—Consisting of ten cards, each bearing an illustration of a soldier prepared, and in the act of hurling an explosive hand grenade. This card is colored blue, hand grenade brown, and other necessary minor colors.

Scout.—The odd suit, consisting of eight cards, each card bearing an illustration of a 70 scout walking across No Man's Land on the outlook for enemy patrols. This card is colored brown, the field green, and contains other minor colors.

The lone card is called Patrol and bears 80 the illustration of a patrol working in No Man's Land.

The manner of playing the game is as follows:

Any suit of the four trump suits may be 85 named trump. These trump suits each contain ten cards. The scout suit cannot be made trumps. Each number (5) card counts five points to side capturing or taking it. Each number (10) card counts ten for side 90 taking it. Each scout card counts ten for side taking it. This includes the number (5) scout card which counts ten. The patrol card counts twenty points for side taking it. There are no counters except the 95 numbers five, ten and scouts and the patrol. The patrol card is at all times a trump. It will not play above the six of trumps, but will take the five of trumps, and of course will take any card that a trump will take, 100 except a higher trump.

All players must follow suit when possible; that is, each player must play a card of the suit led in the trick played, if he has a card of such suit. There are one hundred 105 and sixty points in the game.

The scout cards are numbered from one to eight inclusive. This means that a number eight scout card will take or capture any other scout card. A number two would 110

take a number one, the higher taking the lower.

However, when a scout card is led, the highest card in number of those played in the trick, takes the trick. A trump, of course, is higher in value than a card of another suit. To explain: if a scout card be led, then a number nine be played of a suit not trumps, it would be necessary to play a ten of some suit to capture the trick from the number nine card, unless a trump be played. If, for example, a scout card be led, and the second player plays the eight of machine gun, then the next player plays the nine of trench mortar, the next player must play a ten of any suit to take the trick from the highest card, which in this case is the nine of trench mortar. A trump played, would of course take the trick, because it was a trump. If two cards of the same number be played, on a trick in which a scout card leads, then the first one played is considered high, and if not trumped or beaten by a still higher card, takes the trick.

When four persons are playing the game, each player receives eleven cards. There is a remainder of five cards, which belong to the highest bidder. He discards five cards in place of those he draws, or discards the five he draws, or any part of them, but he must not discard a counter. In case the players decide to discard counters, table rules shall be made to that effect, otherwise, counters are not to be discarded. Any counter discarded may not be added to the count of the opposing player or players, and shall not be counted in the amount made by the bidders. Counters discarded, shall not count for either side.

When three persons are playing the game, the number one, two and three of all the trump suits are removed, and the numbers one, two, three and four of the scout suit are removed from the deck. The counters will then number one hundred and twenty points, and there will be thirty-five cards in

the game. Each player receives ten cards and there is a remainder of five for the highest bidder. Discard and play as in the game for four players.

For a two handed game, discard the four lowest cards of each trump suit and also the sixes, the four lowest scout cards. This will leave twenty-five cards with a total of one hundred and twenty points. Each player receives ten cards, there is a remainder of five cards for the highest bidder. Discard and play as in the game for four players.

If the players do not care to discard any of the scout suit (for which there is no great necessity in a two handed game) each player may receive twelve cards and still have a chance to bid for the remaining five. There will then be one hundred and sixty points in the game.

When more than four persons are playing the cards may be dealt out to all the players, if there is an uneven remainder it may be put in the bidder's pot, or some may be taken from the bidder's pot in order to allow each player to receive his quota of the cards. Play as in the four handed game.

Having thus fully described my invention what I claim as new and desire to secure by Letters Patent, is:—

A card game comprising a deck of cards divided into an unequal number of suits of cards, the odd suit constituting a counter suit in contradistinction to the other suits, any one of which may be designated a trump suit, the cards of every suit rating consecutively in playing value and having distinguishing characteristics whereby the cards of one suit are differentiated from the cards of the other suit, and a master card which is a trump of any suit.

In testimony whereof I affix my signature in presence of two witnesses.

HENRY S. VOGEL.
